UNITED STATES PATENT OFFICE.

PERRY A. McCASKEY, OF LISBON, OHIO.

CREDIT-ACCOUNTING APPLIANCE.

SPECIFICATION forming part of Letters Patent No. 783,126, dated February 21, 1905.

Application filed April 27, 1904. Serial No. 205,094.

To all whom it may concern:

Be it known that I, PERRY A. McCASKEY, a citizen of the United States, residing at Lisbon, in the county of Columbiana and State of Ohio, have invented new and useful Improvements in Credit-Accounting Appliances; and I do declare the following to be a full, clear, and exact description of the invention, reference being had to the accompanying drawings, 10 and to the letters and figures of reference marked thereon, which form a part of this specification.

This invention relates to systems for keeping records of credit sales of merchandise and 15 also the cash payments thereon; and the invention has reference particularly to the apparatus and appliances for carrying out the systems.

The objects are to improve credit systems 20 that are carried out by means of duplicate account-slips or bills and bill-holders in lieu of regular sets of account-books and to improve the various means employed for carrying out such systems as referred to above, so that the 25 apparatus and appliances therefor may be conveniently handled and at the same time be inexpensive in first cost and economical in use.

With the above-mentioned and other objects in view the invention consists in improved 30 apparatus and appliances whereby credit accounts may be recorded and kept, in the novel features of construction of the apparatus and appliances comprised in the means for carrying out the credit system, and in the novel 35 combinations and arrangements of parts, as hereinafter particularly described, and pointed out in the appended claims.

Referring to the drawings, Figure 1 is a 40 perspective view of an improved account-filing cabinet-desk, having a double desk-lid, embraced in the invention; Fig. 2, a perspective view of an improved bill-holder frame and bill-holder without the bill-clips thereof and having devices for rendering the frame 45 and holders portable; Fig. 3, a perspective view of a balance-spring for the bill-holders; Fig. 4, a central vertical longitudinal sectional view of the cabinet-desk, having the bill-holders therein; Fig. 5, a transverse sec-

tional view of the bill-holder-frame base, 50 showing the inner side of one of the upright ends of the frame and a bill-holder in section connected therewith, the holder being broken off; Fig. 6, a perspective view of the cabinet-desk with the double lid raised, so as to show 55 an account-form at the under side thereof; Fig. 7, a side elevation of the bill-holders and their frame detached from their cabinet and yoked together or bunched conveniently for being placed in a safe for protection of the 60 accounts; Fig. 8, a fragmentary sectional detail view showing the manner of connecting bill clamps or clips to opposite sides of the bill-holders; Fig. 9, a plan view of the rear of the forward one of the bill-holders; Fig. 65 10, a plan of the front of the rearmost one of the bill-holders, one of the bill-clamps thereof being broken away and the relative position of the clamp at the opposite side of the holder being indicated by dotted lines; Fig. 11, a fragmentary plan of the index-sheet 70 that is attached to the top of the under part of the double desk-lid; Fig. 12, a fragmentary plan of the form-sheet that is attached to the under side of the under part of the double 75 desk-lid for keeping records of delinquent customers; Fig. 13, a fragmentary plan of the form comprised in the system for tabulating the amounts due from the individual customers at the ends of the months in order to 80 ascertain the total amount due; Fig. 14, a fragmentary plan showing a bill-form held by the improved indexed bill-clamp on a bill-holder, and Fig. 15 a fragmentary plan of the form 85 comprised in the system for tabulating the totals of the amounts due at the ends of the months and years.

Similar reference characters designate like parts or features in the several figures of the drawings. 90

In a practical embodiment of the invention a desk A without legs is provided that is adapted to be supported on store-counters, although legs of course may be provided. The desk has a suitable number of vertical partitions, as a 95 and b, on which a pair of cleats c are secured, the cleats supporting a pad-holder d, on which a pad of bill-forms e may be conveniently kept

and used. The rear portion of the desk has a stationary cover *f* fixed thereto, the plane of the top of the desk forward of the cover being inclined, as is also the holder *d*. The 5 cover *f* has a front ledge *g*. The desk has a double lid comprising an upper part formed as a frame *B*, having a glass table *C* secured therein and a leaf *D* fitting in the frame *B* against the table *C*, the frame *B* being secured 10 to hinges *h*, that are attached to the ledge *g*, and the leaf *D* being secured to hinges *i*, that are attached to the frame *B* at the under side thereof, opposite to the hinges *h*. Thus both 15 parts of the lid may swing upwardly from the desk either together or the frame *B* separately, and when the frame is raised the leaf may swing independently and may be used on which to write on the index-sheet *E*, that is attached to the top thereof. A finger-hold 20 *j* is attached to the free side of the leaf *D* and extends beyond the edge of the frame *B* for manipulating the leaf, and at the under side of the leaf *D* one or more delinquent-lists *F* in sheet form are secured thereto, preferably by means of tacks, so that old lists when 25 no longer needed may be readily detached. When both parts of the double lid are raised, access may be had to the interior of the desk and to the bills *e* in the upper part thereof.

30 A cabinet-case *G*, having a back *k*, is mounted on the cover *f* of the desk *A*, the top and front of the case being open and the cover *f* forming the bottom of the case.

The bill-holder frame comprises a base *H* and 35 two similarly-formed upright ends, as *I*, attached to the base, the frame being removably seated in the case on the bottom thereof behind the ledge *G* and bearing against the back *k*. The frame ends are provided with metal cap- 40 plates *J* *J'*, having each a number of arched caps *J'* formed integrally therewith, so that bearings *l* are provided, in which coiled springs *K* are seated. The frame ends are provided at 45 their inner sides with locking-pins *m*, and the springs have arms *n* engaging the pins, the opposite ends of the springs having arms *p* having bends *q* and adapted when not in use to lie upon the caps *J'*. The back *k* is provided with a catch *r*, that is engaged by a 50 latch *s*, that is connected to the base *H* by a pivot *t*, the latch having an upturned finger-piece *u*. The frame also includes a pair of bearing-plates *L* *L'*, attached to the outer sides of the frame ends, the plates having slots *v* in 55 the upper edges thereof forming bearings for the bill-holder pivots. The bill-holder frame is provided with a yoke comprising a pair of arms *M* and *M'*, that are connected to the lower portions of the frame ends, at the outer 60 sides thereof, by pivots *z*, the arms having at the free ends thereof an integral cross-bar *N*, which is provided with a downturned hook *w*.

The bill-holders, as *O* *O'* *O''* *O'''*, of suitable number are each provided with a pair of pivots *x* and *y*, projecting from opposite sides of

one end portion thereof, the pivots being removably inserted in bearing-slots *v* of the plates *L* *L'*, so that the bill-holders may be removed separately from their frame. The arms *p* of the springs *K* bear against the 70 fronts of the bill-holders and operate in the usual manner to balance the holders. The rear side of the foremost bill-holder and both sides of the other holders are provided with bill-clamps *P* *P'*, identically formed. The holders have holes *1*, and each clamp has two spring-coils *2* and *3* or *5* and *6* and fingers *4* extending from the coils through the holes to the opposite sides of the holders. On the holders having clamps at both sides thereof it will be 80 seen that two clamps are secured by means of two holes, the clamps extending in the same direction at opposite sides of the holder, all toward the free end thereof. Each bill-clamp is provided with a tab-holder *Q*, Fig. 14, having a tab *R* containing indexing-numbers running in regular order, and in some cases the names of customers may be written on the tabs beside the numbers, particularly when customers carry numbered pass-books having detachable duplicate bills or invoices that may not contain the names of the customers, otherwise similar to the form *e*. The tab-holders are conveniently attached to the clamps near the free ends thereof. The bill-holders are 85 provided with rubbers *S* and *T* at opposite sides thereof, so as to prevent interference of the bill-clamps of adjacent holders. The rubbers are secured to the holders by means of clenched 90 nails and are so disposed that the rubbers of one holder engage those of adjacent holders. Ordinarily the bar *N* rests against the back *k* behind the holder *O''*, and when the holders are drawn forwardly so as to stand at angles of about forty-five degrees to the base *H* the 95 yoke-arms *M* *M'* may be moved so that the bar *N* and the hook *w* thereof may engage the top of the holder *O''* and prevent its rearward movement by its balance-springs, the other bill-holders being normally pressed rearwardly by their balance-springs and stopped by the holder *O''* and the bar *N*, as in Fig. 7, so that the actions of the balance-springs may be counteracted, while the bill-holders may be 100 handled in a bunch by means of their frame. 115 The delinquent card-list *F* is suitably ruled, so as to provide a blank column 8 for the register-numbers of the delinquent customers, a column 9 for dates, a column 10 for the names, a column 11 for dollars, and a column 12 for cents. The index-sheet *E* has columns 13 for 120 register-numbers which are to be inserted to correspond with the numbers on the bill-clamp tabs and columns 14 in which to insert the customers' names in alphabetical order. The bill-blanks may be of various convenient forms, but are preferably as heretofore used similar to the form *e* in Fig. 14. 125

As part of the appliances pertaining to the system books are provided having a suitable 130

number of pages having the forms U, on which statements may be made up at the ends of the months, there being on each page a column 15 for register-numbers, a column 16 for customers' names, and twelve columns, as 17 and 18, having the names of the months at their heads and ruled for entering dollars and cents, in which the amounts owing by the customers may be entered and then footed up at the bottom of the columns, thus enabling a dealer monthly to ascertain the balance due from each customer, as well as the total amount due him, according to the balances shown on the duplicate bills on the bill-holders.

15 As a convenience for keeping small accounts against customers who may make only occasional credit purchases the clamp-tabs on the holder O³ are lettered, as indicated in Fig. 10. The free end of each bill-holder is numbered 20 or indexed in the customary manner.

In the back part of each one of the books heretofore referred to are pages having each the form V, having vertical columns 19, 20, 21, and 22, headed, respectively, "Amount on numbers," "Amount on alphabet," "Amount delinquent," and "Total." In another column the names of the twelve months, as 23 and 24, are arranged on horizontal lines. On this form monthly a detailed statement of totals 25 may be made up from the bills on the bill-holders and from the delinquent card-list, so that a dealer may have before him complete data as to what may be due him and from what sources at the ends of the months and at the 30 end of the year, besides the condition of the individual accounts, as shown on the form U, all arranged in one book and the only one desired in the system.

In practical use the bill-holders and the bill-clamps may be employed in the usual manner, the bills being ordinarily hidden by the foremost holder O, and on account of the remaining holders having clamps on both sides thereof of a large number of accounts may be accommodated on comparatively few holders, which is a great advantage. By raising the upper part of the double desk-lid entries may be made on the index-sheet on the lower part or leaf D, and when the latter is held up entries may be made 45 on the delinquent-list, where they may be conveniently referred to. When the frame B is down, the glass table C serves not only to protect the index against soiling, but as a writing-table through which the writings on the index may be read. The bills may be made out on the holder d conveniently, where the balance 50 quickly brought down onto new bills before entries from bills on the bill-holders may be entering charges for new purchases. As is 55 customary, duplicating by means of carbon is practiced, so that an original bill may be given to the purchaser and a duplicate retained on a bill-holder. Each clerk of course may have a pad or book of blank bill-forms, and 60 in some cases customers may be provided with

pass-books having duplex blank bills, which are used in the same manner as the bill-forms in the store. In case a pass-book should not be presented at times when purchases are made the store-blanks may be used and the entries 70 made later from them into the pass-books when presented.

When desirable to place the bills in a safe for protection, the yoke for bunching the bill-holders may be employed, as heretofore described; but when sufficient space is lacking to receive them the several bill-holders may be detached from the bill-holder frame and placed separately in such spaces as may be available in the safe, the subsequent insertion 75 of the bill-holders in their bearings being readily accomplished, as will be apparent from the foregoing description of construction.

In practicing the system the duplicates of original bills are all filed, not only itemized 80 without extra labor, but totaled when each purchase is made. When settlements are made, the cash entries are made on the last bills filed in the bill-holders, although in case of dispute all entries of charges may be referred 85 to. At the ends of the months the forms U and V should be used to tabulate the results of the credit business as shown on the bill-holders or account-slips thereon. Additional tabulating-forms of course may be employed, 90 if desired, as a further extension of the system without the necessity of making the daily book-entries heretofore largely practiced.

Having thus described the invention, what I claim as new is—

1. Account-recording appliances including a frame provided with inserted detachable bill-holders, and balance-springs for the bill-holders mounted on the frame.

2. Account-recording appliances including a frame and pivoted bill-holders provided with a yoke for temporarily preventing pivotal movements of the bill-holders relatively to the frame.

3. Account-recording appliances including a cabinet-desk provided with a double lid comprising two hinged parts coöperating one with another, one part of the lid having a glass table forming a part thereof, and bill-holders coöperating with the lid.

4. Account-recording appliances including bill-holders, a cabinet-desk for supporting the bill-holders provided with a double lid comprising two parts coöperating one with another and having an index-sheet between the two parts thereof.

5. Account-recording appliances including indexed bill-holders, a cabinet-desk for supporting the bill-holders provided with a double lid comprising a lower part and an upper part, and an index-sheet on the top of the lower part of the double lid.

6. Account-recording appliances including indexed bill-holders, a cabinet-desk for supporting the bill-holders provided with a double

lid comprising a hinged frame having a glass table and having also a leaf hinged to the frame, an index-sheet on the top of the leaf, and a delinquent-list sheet on the under side 5 of the leaf of the lid.

7. Account-recording appliances including a bill-holder frame having pivot-bearings therein, bill-holders having pivots mounted in the bearings, and balance-springs for the 10 bill-holders mounted independently on the frame and coöperating with the bill-holders.

8. Account-recording appliances including a bill-holder frame having slots in the ends thereof, bill-holders having pivots mounted 15 removably in the slots, and balance-springs mounted independently on the frame and having detachable connection with the bill-holders.

9. Account-recording appliances including a bill-holder frame, bill-holders pivoted on the 20 frame, a yoke comprising a pair of pivoted arms and a cross-bar provided with a hook adapted to engage one of the bill-holders, and balance-springs mounted on the frame and coöperating with the bill-holders.

10. Account-recording appliances including a bill-holder frame having caps, balance-springs retained by the caps and having arms bent over and adapted to lie upon the caps, and bill-holders pivoted on the frame so as to 25 be opposed by the arms when the latter are raised from the caps.

11. Account-recording appliances including a bill-holder frame, bill-holders mounted on the frame, balance-springs for the bill-holders, and bill-clamps mounted on the bill-holders and provided with index-tabs. 35

12. Account-recording appliances including a bill-holder frame, bill-holders mounted on the frame and having pairs of apertures 40 therein, bill-clamps mounted oppositely on both sides of the bill-holders and having members extending through the apertures to opposite sides thereof, the bill-clamps on both sides of the bill-holders extending from the 45 apertures in the same direction.

13. Account-recording appliances including pivoted bill-holders, bill-clamps mounted on the bill-holders, tab-holders attached to the bill-clamps near the free ends thereof, and 50 index-tabs mounted on the tab-holders.

14. Account-recording appliances including a case, a bill-holder frame inclined in the case, bill-holders pivoted to the bill-holder frame, and balance-springs mounted on the 55 bill-holder frame and having detachable connection with the bill-holders, the springs being removably supported independently of the bill-holders.

15. Account-recording appliances including a bill-holder frame, bill-holders mounted on the frame and having pairs of apertures therein, bill-clamps mounted oppositely on both sides of the bill-holders and having members extending through the apertures to opposite sides thereof, and rubbing-strips on 65

the bill-holders in pairs on opposing holders and coöperating one with another.

16. Account-recording appliances including a case having a back provided with a catch, a bill-holder frame having a latch coöperating with the catch, bill-holders mounted on the bill-holder frame, and balance-springs mounted on the bill-holder frame coöperating with the bill-holders. 70

17. Account-recording appliances including a bill-holder frame provided with balance-springs supported independently thereby, and bill-holders mounted removably on the bill-holder frame independently of the balance-springs and having coöperating engagement therewith. 75

18. In account-recording appliances, the combination with a cabinet-desk, of a bill-holder frame having ends provided with bearings, bill-holders having pivoting devices coöperating with the bearings, and springs supported by means of the ends of the frame independently of the bill-holders for balancing the holders uprightly. 80

19. In credit-accounting appliances, the combination of a cabinet-desk provided with a double lid comprising an upper part having a glass table and hinged to the desk and a lower part hinged to the upper part and having a finger-hold at the free end thereof coöperating with the upper part, a frame mounted in the cabinet-desk, and bill-holders mounted on the frame. 85

20. In account-recording appliances, the combination with a cabinet-desk having a case 100 provided with a back and also a ledge on the bottom thereof, of a bill-holder frame leaning against said back behind said ledge, bill-holders pivoted on the frame, balance-springs mounted on the frame and coöperating with the bill-holders, a catch attached to said back, and a latch mounted on the bill-holder frame adapted to coöperate with the catch. 105

21. In account-recording appliances, the combination with a cabinet-desk, of a bill-holder frame having ends provided with bearing-plates having slots, bill-holders having pivots removably inserted in the slots, and springs mounted on the ends of the frame and having each a locked arm and also a swinging 110 arm coöperating with a bill-holder and adapted to be disconnected therefrom. 115

22. In account-recording appliances, the combination with a plurality of pivoted bill-holders, of a plurality of bill-clamps mounted 120 on the holders, tab-holders attached to the bill-clamps, and index-tabs attached to the tab-holders.

In testimony whereof I affix my signature in presence of two witnesses.

PERRY A. McCASKEY.
